UNITED STATES PATENT OFFICE.

ALFRED HEAVEN AND ROBERT SMITH, OF MANCHESTER, ENGLAND.

IMPROVEMENT IN EMBROIDERING-MACHINES.

Specification forming part of Letters Patent No. 38,358, dated April 28, 1863.

To all whom it may concern:

Be it known that we, ALFRED HEAVEN and ROBERT SMITH, both of the city of Manchester, in the county of Lancashire, Great Britain, have invented a new and useful Machine for Embroidering by Steam or other Motive Power; and we do hereby declare that the following is a full, clear, and exact description of the construction and operation of the same, reference being had to the annexed drawings, making part of this specification.

Our invention is applicable to such machines as are used for embroidering on cloth in which the material is stretched in a vertical frame, on each side of which frame is a nipper mechanism for grasping a threaded needle. This nipper mechanism takes the needle from the cloth, and presents it to the cloth at points regulated by a pattern and pentograph machinery, and the needle employed is a double-pointed instrument carrying a thread through its center and passing entirely through the cloth, the nippers on one side of the cloth holding it with its opposite point presented through the cloth until the nippers on the other side grasp it to carry it therefrom and form the stitch.

Though we shall describe the nipper mechanism as operating only one needle, any convenient number of them are to be used, they all operating in the same manner.

We would now remark that as neither the construction and arrangement of the pattern, the pentograph, nor the nippers form any part of our present invention, and are not necessary to be particularly understood to comprehend our invention, being also well known to persons skilled in the art of machine embroidering, they are not particularly shown in the drawings, nor will they be further described, other than to observe that the nippers are the instruments which grasp and draw taut the thread to produce the strain thereon, for the purpose hereinafter to be described.

Our invention consists in the arrangement of mechanism to carry the nipper-carriage back and forth to and from the cloth-frame, in the mechanism for shifting the driving-belt of said carriage onto the fast and loose pulley, and in the employment of the strain produced on the thread as it is drawn out from the cloth to actuate the shifting mechanism.

Sheet 1 of the drawings represents an end elevation of the embroidery-frame with the

machinery on one side thereof, (the exact counterpart of which machinery is placed on the other side thereof.) Sheet 2 shows a front elevation of one end of the machine.

D denotes the embroidery-frame, hung midway in a frame-work, A, and having the operating or embroidery mechanism on each side thereof, excepting the shaft U and its immediate connection which are employed to give movement at the proper time to the mechanism on either side of the embroidery-frame, according as one or the other nipper-carriage is being operated. B is the nipper-carriage, one or more of which can be used on each side of the frame D, as one or more needles are to be used. The carriage B traverses to and from the frame D over ways C on each end of the carriage. The mechanism producing these to-and-fro movements of the carriage is as follows: Each guideway C has a toothed rack, a' , into and along which works a toothed wheel, Q, fixed on a shaft, P, turning in bearings on the carriage B. One end of a band, E, coils around a pulley, o, on the said shaft P, while the other end of the band coils or winds around a pulley, b', fixed on the shaft of a rotating gear, N, which meshes into and is worked by another gear, N', placed on a shaft carrying fast and loose pulleys M. The pulleys M are worked by a band, J, running over pulley M and another pulley, L, which latter has a bevel-wheel, K, on its shaft, meshing into and driven by a bevel gear, K', fixed on the power-shaft H, which is driven by any proper motive power. Motion being given to shaft H (when the belt J is on fast pulley M) in the proper direction, it rotates the gear N and pulley b', and causes the band E to wind around the latter. This unwinds the band from the pulley o, rotating it and the gear Q, which rotation of gear Q causes it to run over its rack a' , thereby drawing the nipper-carriage away from the cloth-frame, pulling the needle and thread with it to make and tighten the stitch. When the carriage B has completed its outward movement and the belt J has been shifted, by means to be hereinafter described, onto the loose pulley M, the gears N N' are left free to rotate and permit the carriage B to return to the frame D, which return is produced as follows: One end of a strap, F, is fastened to a projection, V, of the carriage B, while the other end is fastened upon a compound pulley, W, to which is hung

a weight, Z, the weight of which is sufficient to pull back the carriage B to the frame D. Instead of using the compound pulley, the strap F may pass immediately over the pulley W, and, depending therefrom, have the weight Z attached to its lower end. When the carriage B is up to the cloth-frame and ready for its next outward movement the belt J is to be shipped onto the fast pulley, which is done by the following mechanism.

U is a vertical rotary shaft, bearing on its lower end a friction-drum, V, and being hung so as the drum V shall be capable of a swinging motion, to bring it at the proper time into contact with either one of two friction-drums, W W, according as we may wish to operate the needle or nipper-carriage B on either side of the frame D. A bevel-gear, Y', on top of shaft U, actuates a bevel-gear, Y, on a shaft, X. Said shaft X carries a tappet, b, (see Sheet 2,) the lower end of which, as tappet rotates, strikes against a swivel-catch, e, hung upon a lever or rod, d. A weight, e', serves to keep or bring catch e into position. The rod d is bent up, as seen at e, or d and e may be two rods confined together. The rod e at top is jointed to and so as to actuate a small shaft, g, rotating in bearings e', affixed to one of the guideways C.

Depending from the outer end of the shaft g and turning with said shaft is a connecting and shipping rod, f, which, by a projection, f', thereon or in connection with a projection, f'', from a bar, k, straddles the belt J. Therefore when the drum V is brought by the operator into contact with the drum W on that side where the nipper-carriage is to be operated, rotation is given through shaft U and gears Y and X to tappet b in such manner as to carry the catch e and rod d sidewise, the catch e taking the position seen in Sheet 2 by dotted lines. This gives a lateral movement to rod e, causing the shaft g to be rotated slightly, thus imparting a lateral movement to connecting-rod f where it passes the belt J, so that the fork of the rod f' (or the rod f and projection f'') shall ship the belt J from the loose onto the fast pulley M.

We will now describe the mechanism for shipping the belt J from the fast onto the loose pulley at each expiration of outward movement of the carriage B, and the manner in which we employ the thread to act on this mechanism.

The thread R passes under a wire or rod, a², extending across and in front of the nipper-carriage B, and connecting two levers or fallers, s, placed near the opposite ends of the carriage, and springing from a rocking shaft, u, on one end of which a crank, u', is fixed, to which crank a connecting-rod, u², is jointed, connecting the crank u' and its shaft u with another crank, u³, placed on a shaft, u⁴, which

lower shaft, u⁴, may or may not have fallers s and rod a², connected thereto. From this shaft u⁴ a lever, t, depends, so as to come into contact with a rocking bar, n, kept in position, except when operated upon by the lever n, by a weight, p. This rocking bar turns on a pivot, m, extending from an ear or projection, n', from the bar. (See Sheet 2.) A stud, q, from said ear n' bears against the under surface of the bar k, before spoken of. The bar k has a catch, k', into which a tooth, l, catches. The rod f, before spoken of, connects bar k with the shaft g, and from this shaft g a bar, j, rises, which has a retracting-spring, h, connecting it at top with the frame-work A. This mechanism operates as follows: When in the movement of the carriage B from the frame D the thread tightens, the strain produced by its pull raises the rod a², which turns the shaft u, and through the cranks u', u² and connecting-rod u² turns also the shaft u⁴. This depresses the lever t, which pushes down the bar n, raises the stud q, and through it the bar k, releasing the catch k' from the tooth l. As soon as the catch k' is thus released the retracting-spring h at top of bar j turns the shaft g, and thereby allows the rod f (or rod f' and stud f'') to ship the belt onto the loose pulley. Upon the loosening of the thread, as the carriage B begins its return movement, the weight of the fallers s brings the rod a² and connecting-rods, cranks, and shafts u, u', u², u³, and u⁴ and lever t back to their normal position, while the weight p rights the lever n and stud q, so that when the belt J is next shifted onto the fast pulley the bar k will be pushed in, so that the catch k' shall slip over the tooth l and confine the belt upon the fast pulley until the stud q again releases the bar, and the spring h carries it back and ships the belt.

Having thus described our machine, we will remark that we do not intend to confine ourselves to the precise details of mechanism herein described, but intend to vary the same as circumstances may dictate or require.

What we claim is—

1. The combination of mechanism herein described for giving the carriage B its motion to and from the frame D, when such mechanism is used in combination with the shipping mechanism, as set forth.

2. The mechanism, substantially as described, for shipping the belt J from the fast onto the loose pulley and from the loose onto the fast pulley, for the purposes as set forth.

3. The employment of the tightened threads to actuate the shipping mechanism, as above described.

ALFR. HEAVEN.
ROBERT SMITH.
